UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

METAL-REDUCING MACHINE.

1,084,628.

Specification of Letters Patent. Patented Jan. 20, 1914.

Application filed April 15, 1913. Serial No. 761,271.

To all whom it may concern:

Be it known that I, BENGT M. W. HANSON, a citizen of the United States, residing at Hartford, in the county of Hartford and 5 State of Connecticut, have invented certain new and useful Improvements in Metal-Reducing Machines, of which the following is a specification.

This invention relates to metal-reducing machines, one of the primary objects of the 10 invention being to provide a machine of this character having greater efficiency than those generally in use and by which the work can be readily and quickly mounted and dis- 15 mounted.

The invention comprises other features of 20 novelty and utility which with the foregoing will be set forth at length in the following description wherein I will outline in detail that one of the several forms of embodiment of the invention which I have selected for illustration in the drawings accom- 25 panying and forming part of the present specification, this showing being made to enable those skilled in the art to practise the invention. From this statement it will be clear that I do not restrict myself to such disclosure; I may depart therefrom in several respects within the scope of the invention 30 defined by the claims following said description.

Referring to said drawings. Figure 1 is a side elevation partly in section, of a metal-reducing machine involving my invention. 35 Fig. 2 is a top plan view partly in section, of work supporting means, the reducing member removed. Fig. 3 is a longitudinal section on the line 3—3 of Fig. 2. Fig. 4 is a transverse section on the line 4—4 of 40 Fig. 2.

Like characters refer to like parts throughout the several figures of the drawings.

I provide means whereby a metal-reducing member can operate simultaneously on 45 several pieces of work, and owing to this condition increase materially the efficiency of the machine as compared with those of the old type. Any desirable number of pieces of work may be concurrently reduced, 50 although in the showing made there are two work-holders provided. The work-holders and the reducing-member may vary as to nature, although as a means for directly sustaining the work, turn tables act satisfactorily 55 while the reducing member may consist

of a grinding wheel of emery or its equivalent, which form of wheel is customarily used for grinding surfaces, being in fact familiarly known as "surface grinding" wheel. The work-holders are preferably opposite the reducing member when in working relation, and I prefer also that the working surface of the reducing member overlap simultaneously the work-supporting portions of the work holders whether they be in the form of turn-tables or some other devices. In addition to increasing the efficiency of the machine as already alluded to, I can bring to a standard size, several pieces of work which vary in depth or other dimensions. I prefer also that the reducing member and work holders be relatively movable transversely of the axis of rotation of the reducing member which result is conveniently secured by mounting said work-holders on a traveling carriage or table.

The different operative parts of the machine may be supported by any suitable framework, that shown comprising the base 2 and the column or standard 3 rising from 50 said base or bed, the reciprocating or traveling platen 4 being mounted for movement upon said base or bed. Fastened in some suitable way, as by bolting, to said carriage or platen 4, is the plate 5 which carries the 55 work holders or supports 6 and 7 which, although as shown as consisting of turn tables, might be of any other desirable character.

As the two turn-tables 6 and 7 are the same in construction, mounting and operation in the present instance, a detailed description of such features with respect to one, will apply to the other, and in this connection specific reference may be had to the turn table 6. The turn table 6 is mounted 60 upon the supporting body 8 which has an approximately central opening to rotatively receive the pendent hollow or tubular shaft or journal 9 of said turn table, the latter also being provided with a face-plate 10 fastened 65 suitably rigidly in place as by screws 11. To this face plate 10 the work is directly fastened by clamps, bolts or any of the other means now commonly employed for this purpose. Between the body of the turn table 6 and the supporting body 8 there may as 70 shown be interposed the wear ring 12 of some suitable material.

The rotary shaft 13 supported by suitable bearings on the plate 5 presents a suitable 75

center for the two supporting bodies 8, although said supporting bodies 8 do not directly engage said shaft 13. As will hereinafter appear said shaft 13 is operatively connected as by gearing, with the two turn tables 6 and 7 for simultaneously rotating the same. Surrounding the shaft 13 are axially alined bushings 15 and 16, the adjacent ends of which are separated or spaced 10 from each other for a purpose that will hereinafter appear. The supporting bodies 8 are shown provided at their inner ends with half sleeves 17 which embrace the bushing 18 which incloses the axially alined bushings 15 and 16. The bushings 15 and 18 are connected to each other for instance by the screw 19 which latter is also utilized to hold in place the stub or thrust shaft 20 between which and the shaft 13 the anti-friction ball 21 is interposed. The bushing 18 is also united with the bushing 16 for instance by the screw 22. In view of the construction described the end thrust of the shaft 13 is applied equally to the two bushings 15 and 16. Such thrust is initially applied to the ball 21 being transmitted from the latter to the stub or thrust shaft 20 and through the screw 19 to the bushing 18 which owing to its described connection with 25 the bushing 16 imparts such thrust also to the latter.

Means are provided, such as by divided boxes 23, for maintaining the supporting bodies 8 in operative relation with the pivot 35 or bushing 18, and these divided boxes, the sections of which are held removably assembled by screws or bolts 24, surround the terminal portions of the half sleeves 17 to maintain the latter in proper relation with 40 said bushing 18. The two supporting bodies can, therefore, be tipped or tilted about the axis of the shaft 13 to angularly adjust the turn tables. In the construction shown screws as 25 are tapped into the under sides 45 of the two supporting bodies 8 near their outer terminal portions and bear upon the upper surface of the plate 5; by the manipulation of these two screws 25 the two supporting bodies can be readily adjusted and 50 preferably the adjusted relation is positively maintained in some suitable manner as by the holding or check screws 26 also tapped into the supporting bodies and which are adapted to force the shoes or blocks 26' 55 against the adjusting screws 25 to maintain the desired relation.

In the organization shown the two turn-tables are rotated by worm gearing and the shaft 13 is represented as provided with a 60 worm 27 in mesh with the worm gears 28 located in chambers in the under sides of the respective supporting bodies 8 and fastened to the respective hollow shafts or journal members 9 by screws 29 or in some other 65 suitable manner. It will, therefore, be clear

that when the shaft 13 is rotated the two turn tables 6 and 7 through the intermediate gearing will be simultaneously rotated. The open under sides of the two bodies 8 can as shown, be closed by plates 30 and the screws 25 to which I have referred extend through perforations in these plates. It will be seen that the place of mesh between the worm 27 and the two gears 28 is between the inner ends of the bushings 15 and 16; and it will be also seen that the outer bushing 18 has diametrically opposite slots 31 through which the rim portions of the two worm gears 28 extend to mesh with the worm.

Any suitable means may be provided for 80 rotating the shaft 13, the following having been found satisfactory: Fastened to the rear of said shaft 13 is the beveled gear 52 in mesh with the beveled gear 53 fastened to the shaft 54 carried by an arm 55 on the framing of the machine. Said shaft 54 has keyed or otherwise fastened to it a pulley 56 connected by a belt 57 with the pulley 58 fastened to the shaft 59 supported by the arm 60 on the framing and driven by a belt 61 around the pulley 62 also fastened thereto. The belt 61 is preferably, but not necessarily continuously operative, the same statement applying to the two turn tables 6 and 7 which through the intermediate described 90 parts receive their motion from said belt 61.

The grinding or reducing member is denoted by 32, and although it is shown as being above the two work holders 6 and 7, this is not essential in all cases. In the construction shown the axis of rotation of said reducing member is substantially parallel with the axes of rotation of the two work holders or turn tables 6 and 7. I say "substantially parallel" in that the two tables 100 are susceptible of angular adjustment which although quite desirable is not always necessary. It will be noted that the working surface of the grinding wheel or disk 32 overlaps the work supporting portions of the 110 two turn tables 6 and 7 and that although this overlapped relation continues approximately as far as the axis of motion of each of the turn tables, this may not be required in all cases, one of the prime considerations being as intimated that the working surface of the tool overlap the work supporting portions of the several work supports which may be obtained for instance, by having said tables opposite the tool. Owing to the relation of the wheel with the two turn tables, I can grind the work in such manner that the faces of the work when ground, will be at an exact right angle to the axis of rotation of the reducing wheel or the ground surface of the work can be either convexed or concaved, or one piece can be ground flat and another concaved or convexed, or one concaved and another convexed. As already intimated there may be any number of 120 125 130

these work holders 6 and 7. Said parts 6 and 7 constitute in fact auxiliary work supports or holders, the traveling table or platen 4 to which reference has already been made, 5 constituting a main work support or holder. It will be perceived that the space between the two auxiliary work supports 6 and 7 and the reducing member 32 is open and unobstructed, by reason of which I can freely relatively shift the said auxiliary work holders and reducing wheel transversely of the axis of rotation of said reducing wheel in order to facilitate the application of work in the rough and the removal of the finished work from said 10 auxiliary work holders or supports. As intimated this result can be obtained either by laterally moving the reducing wheel or by moving the said auxiliary work holders in a direction transverse to the axis of rotation 20 of said reducing wheel, but I prefer that the result in question be obtained by simultaneously shifting said auxiliary work holders, which is one of the reasons that I mount them upon a shiftable main support of which 25 the platen or carriage 4 is one of several illustrations. As to this aspect of the case, therefore, it will be evident that the relation is broad, not residing in the construction illustrated in the drawings.

30 In the organization illustrated the reducing wheel 32 is fixed to the shaft 33 supported by the adjustable bracket 34 hereinafter described, said shaft being equipped with collars 35 and 36 engaging said bracket or bearing 34. The upper end of said shaft 33 has a vertical sliding movement through the bracket or bearing 37 from which it will be clear that the shaft of the reducing wheel 32 extends upward therefrom, while the shafts 40 of the two auxiliary work supports or turn tables 6 and 7 extend downward therefrom. The shaft 33 can be driven in any desirable manner, for instance by the belt 38 extending around a pulley 39 splined to said shaft 45 33 and guided between its ends by a sheave 40 on the column 3. In practice the reducing wheel is continuously driven, although it may be intermittently operated if desired. It will be clear that the reducing wheel 32 and shaft 33 partake of the movements of the adjustable bracket 34, so that when the latter is shifted the reducing wheel will be either raised or lowered, said reducing wheel during the reducing operation being preferably given a feed movement which in the organization shown is in a downward direction which is preferable although not essential.

50 The column 3 has ways to receive and guide the bracket 34 which may be operated in any desirable manner; the means shown for this purpose will now be described. Fas- 55 tened to the column is the stationary rack 41 in mesh with the pinion 42 fastened to the shaft 43 rotatively supported by the

bracket 34, said shaft 43 also having fixed to it a worm gear 44 in mesh with the worm 45 rigid with the shaft 46 rotated in any suitable manner. During the reducing operation the shaft 46 is being rotated, so that 70 through the intermediate described parts the reducing wheel 32 will be advanced to grind the pieces of work on the several work holders 6 and 7.

Any suitable means may be provided for 75 moving the carriage or main work support 4 on its ways on the bed 2, it being understood that said movement is from side to side of the bed; the means shown for this purpose will now be set forth. Said main support 4 is shown provided with a depending flange 47 extending through an opening in the top of said bed 2 and having fastened to it a rack 48 in mesh with the pinion 49 fastened to the shaft 50. It will be clear that by rotating said shaft 50 the carriage or platen 4 can be shifted along the bed so as to get the work holders 6 and 7 from under the reducing wheel 43 for the purpose of mounting work to be ground on said work holders or for dismounting work that has already 80 been ground. The shaft 50 can be operated either by power or hand as common in this and allied arts.

What I claim is:

1. In a machine of the class described, the combination of a plurality of independently-adjustable work supports, and a rotary reducing member common to said work supports and movable in the direction of its 95 axis of rotation.

2. In a machine of the class described, the combination of a plurality of work supports, a rotary reducing member common to said supports, and means for moving said supports transversely of the axis of rotation of the reducing member.

3. In a machine of the class described, the combination of a plurality of work supports, a rotary reducing member to act simultaneously upon several pieces of work carried by the respective supports, and a support upon which said work supports are mounted, movable in a direction transverse to the axis of rotation of said reducing member.

4. In a machine of the class described, the combination of a plurality of work supports, a reducing member opposite the work supports to act simultaneously upon several pieces of work carried thereby, the space between the work supports and reducing member being open and unobstructed, means for supporting said reducing member opposite the portion thereof adjacent to the work supports, and means for supporting the work 110 supports opposite the parts thereof adjacent to the reducing member.

5. In a machine of the class described, the combination of a rotary shaft, a pair of adjustable supports movable about said shaft 125

as a center, turn tables carried by the respective supports, a reducing member disposed opposite the respective turn tables, the active surface of the reducing member simultaneously overlapping the work supporting portions of the turn tables, and means operable by said shaft for simultaneously rotating the turn tables.

6. In a machine of the class described, the combination of a rotary shaft, a bushing surrounding said shaft, a pair of supports provided with half sleeves embracing said bushing, divided boxes surrounding the half sleeves to maintain the same in assembled relation with said bushing, turn tables on said supports, means operable by said shaft for simultaneously rotating the turn tables, and a reducing member disposed opposite the turn tables, the active surface of the reducing member simultaneously overlapping the work supporting portions of both turn tables.

7. In a machine of the class described, the combination of a rotary shaft, a bushing surrounding said shaft, a pair of supports having half sleeves fitted against and turnable upon said bushing, means for holding the half sleeves in assembled relation with said bushing, turn tables on said supports, and means for transferring the effect of said shaft to said turn tables for simultaneously rotating the latter.

8. In a machine of the class described, the

combination of a rotary shaft, a bushing surrounding said shaft, supports provided with partial sleeves fitting against and turning upon said bushings, split boxes inclosing the said partial sleeves, for maintaining the same in assembled relation with said bushing, turn tables on the respective supports, and means operable by said shaft, for rotating the turn tables.

9. In a machine of the class described, the combination of a rotary shaft, a pair of bushings inclosing the shaft and separated from each other, a thrust shaft disposed within and connected to one of the bushings, an anti-friction ball between the two shafts, a second bushing inclosing the other bushings and rigidly connected to them, a worm fastened to said shaft between the ends of the first mentioned bushings, a pair of worm gears in mesh with said worm, the outer bushing being slotted for the passage of said worm gears, a pair of adjustable supports movable about the axis of said rotary shaft, and turn tables on the respective supports, rigidly connected with the respective worm gears.

In testimony whereof I affix my signature in presence of two witnesses.

BENGT M. W. HANSON.
